CLARE H. DRAPER, OF HOPEDALE, MASSACHUSETTS, ASSIGNOR TO CLARE H. DRAPER AND CHARLES F. ROPER, COPARTNERS TRADING AS C. F. ROPER & COMPANY, OF HOPEDALE, MASSACHUSETTS.

ENVELOP MOISTENER AND SEALER.

1,169,118.

Specification of Letters Patent.

Patented Sept. 1, 1914.

Application filed September 26, 1913. Serial No. 792,051.

To all whom it may concern:

Be it known that I, CLARE H. DRAPER, a citizen of the United States, and resident of Hopedale, county of Worcester, and State of Massachusetts, have invented an Improvement in Envelop Moisteners and Sealers, of which the following description, in connection with the accompanying drawings, is a specification, like letters on the drawings 10 representing like parts.

The invention to be hereinafter described relates to envelop moisteners and sealers of the general character of that set forth by the patent to Jonas Northrop, No. 1,051,751, 15 January 28, 1913, and the aims and purposes of the present invention are to improve such character of moistener and sealer in several particulars, whereby a more efficient and reliable device is provided, all as will be hereinafter more fully described in connection 20 with the accompanying drawings showing one practical form or embodiment of the invention, it being understood, however, that the invention is not restricted to the particulars of means shown, but is definitely set forth in its true scope by the claims.

In the drawings:—Figure 1 is a plan view of an envelop moistener and sealer embodying one form of the present invention; Fig. 2 is a side elevation thereof, the parts being shown in normal position; Fig. 3 is a section on the line 3—3, Fig. 1, the parts being shown enlarged for the purpose of clearness; Fig. 4 is a similar section on line 4—4, Fig. 1; and Fig. 5 is a view showing the general form of the part for directing the flap of the envelop downward and the body of the envelop upward as the latter is moved over the device.

The supporting frame for the sealer and moistener may be of any appropriate character, and as shown it comprises a base 1 from which rise the end walls 2 and side walls 3, Figs. 3 and 4. This base, and side 45 and end walls may conveniently comprise a box-like structure, substantially as indicated by the drawings, although it is to be understood that any suitable support appropriate for the purposes will be within the true 50 scope of the invention. In the illustrated form of the invention, the side and end walls may conveniently be secured to the base by the corner brackets 4.

Extending upward from the base 1 and

within the box inclosure are the posts 5, 55 preferably one at either end of the frame and between said posts and one of the walls 2 is placed a moistener tank 6. This tank may be appropriately formed of metal, although this is not important, and has a wall 60 7 provided with a flanged part 8 on which rests a wick or other moisture-absorbing substance 9, the end of which extends down into the liquid 10 in the tank. The top wall 11 of the tank may be provided with a suitable cap 12 which may be removed when it is desired to replenish the tank. The top wall 11 of the tank preferably extends at 13 over the flange 8 of the wall 7 and projects beyond the same, as indicated by Fig. 3. 70 The wick or other moisture-absorbing fabric 9 may be clamped between the walls 8 and 13 by means of a suitable clamp 14, the construction being such that when the wick or moistening fabric is in place, the end 15 thereof will extend beyond the walls 8 and 13 a suitable distance to provide a moisture-applying means for an envelop, as will hereinafter more fully appear.

Hinged at 16 to supporting arms 17 rising from the corner posts 4 is the sealer plate 18. This sealer plate, as indicated by Fig. 1, extends from side to side of the supporting frame, and is normally held with its free edge in raised position, substantially as in Fig. 3, by a spring 19, shown by dotted lines in Fig. 1, and in Fig. 4. This spring is preferably of the torsional type, and is contained within the recess 20 in the rear edge of the sealer plate, substantially as indicated in Fig. 4. The spring 19 preferably surrounds a rod 21 in said recess and one end of the spring, as indicated in Fig. 4, engages the wall of the recess as at 22 and its other end 23 contacts with the inner surface of the wall 2, the construction being such that the spring 19 normally holds the sealer plate in inclined position, as indicated by Figs. 2 and 3. If desired, the sealer plate 18 may be provided with a pad or roughened 90 surface 24.

Resting with one edge upon the lugs 25, one at each corner at the front of the supporting frame, is the moistener plate 26, having secured thereto the arms 27, one 105 near each end of the moistener plate. These arms 27 are preferably contained in recesses formed in the substance of the moistener

plate 26, substantially as indicated by Figs. 2 and 4, and are secured therein by suitable means, such as the pins 28, the construction being such that the arms 27 are substantially rigid with the moistener plate 26. The arms 27 extend from the moistener plate toward the sealer plate 18, and are received in recesses 29 formed in the under surface of the sealer plate 18, where such arms 27 have their extensions 30 pivotally connected to the sealer plate by the pins 31, Fig. 4, the construction being such that while the arms 27 are secured rigidly to the moistener plate and the extensions 30 thereof are secured 10 pivotally to the sealer plate, the action of the springs 19 upon the sealer plate will cause the sealer and moistener plates to assume normal position, as indicated by Fig. 3, wherein the adjacent edge portions of the moistener and sealer plates are in different planes.

In order that the position of the adjacent edges of the sealer and moistener plates may be properly assumed, as indicated in Fig. 3, the extensions 30 of the arms 27 secured to the moistener plate are each provided with an arm 32 having an end portion 33 adapted to contact with a pad 34 secured to the under surface of the sealer plate 18, whereby when the spring 19 raises the sealer plate by turning the same about its pivotal support 16, the stop 33 will contact with the pad 34 and properly limit the upward movement of the free end of the sealer plate under the action of said springs, and perforce also the upward position of the adjacent edge of the moistener plate 26.

From the construction hereinbefore described, it will be apparent that the springs 19 acting upon the sealer plate 18 will normally hold the sealer plate and moistener plate yieldingly in the position indicated by Fig. 3, wherein the free edge of the sealer plate will be in somewhat higher position than the adjacent edge of the moistener plate. The parts being in this position, it is the purpose of the present invention that when an envelop *a* is placed upon the moistener plate with its flap *b* opened out, as indicated by Fig. 3, and then moved in the direction of the arrow, Fig. 3, the flap *b* of the envelop will be securely and unerringly engaged by the opposed edge of the sealer plate and deflected downward to thereby cause the said flap to wipe over the end 15 of the moistener 9 as the body part of the envelop passes over the space between the edges of the moistener and sealer plates, all 20 substantially as indicated by Fig. 4. As the hand moves the envelop in the direction of the arrow, it presses downward also, thereby facilitating the action of the sealer plate edge in thus deflecting the flap into contact 25 with the moistening device within the frame-

work, as indicated in Fig. 4, and bringing the top surfaces of the sealer and moistener plates in substantially the same plane so that the envelop may pass with ease from the moistener plate 26 onto the top of the 70 sealer plate 18, and the flap be drawn over the moistening device and properly sealed, as will be readily understood.

In the construction disclosed by the patent hereinbefore noted, the edge of the sealer plate was curved or turned over uniformly throughout the length of said plate. The present invention modifies this construction materially and by such modification secures the unerring action hereinbefore referred to. 80

Hereinbefore the parts 18 and 26 have been termed sealer and moistener plates, respectively, for the purpose of identification, but it is to be understood that these terms are not terms of limitation. Correspondingly, for the purpose of identification, the part of the sealer plate which acts upon the flap and body of the envelop in effecting the moistening and sealing thereof, may be conveniently termed the flap and envelop director. 85

In the form of the invention shown, the flap and envelop director 35 comprises a plate preferably secured to the free end portion of the sealer plate 18 by lugs 36, though 90 it is obvious that the flap and envelop director might be otherwise connected to the sealer plate 18, if desired. The flap and envelop director, whether made integral with or separate from the sealer plate 18 and secured thereto, extends toward the edge of the moistener plate, Figs. 1 and 3, and has its side portions curved downwardly so that the edges of said side portions project below the adjacent edge of the moistener plate 105 when the parts are in normal position, as indicated by Figs. 1 and 3. Between these side portions, however, the flap and envelop director has a reentrant part or is cut away as at 37, Figs. 1 and 5, so that the edge of 110 the reentrant or cut-away portion is normally above the plane of the moistener plate and the edge thereof, and from the said central reentrant or cut-away portion the edge of the flap and envelop director curves gradually downward and outward toward the sides thereof below the adjacent edge of the moistener plate. The purpose of thus providing a cut-away central or reentrant portion of the flap and envelop director and 115 having the plates normally sustained with such portion above the plane of the moistener plate, is to provide means, such as the edge of such portion, that will be in position above the end of the envelop flap as the envelop is moved over the moistener plate and to insure that the flap shall be engaged and pass thereunder as the envelop is moved forward. It is equally important, however, 120 that the body of the envelop shall not follow 125 130

the flap thereof to a position below the flap and envelop director, therefore the reëntrant or cut-away portion 37 is curved downwardly and outwardly so that the side 5 edge portions of the flap and envelop director as at 38, separated a distance less than the length of an envelop, shall be normally positioned below the adjacent edge or plane of the moistener plate. From this construction, as indicated by Fig. 1, it will be apparent that when the envelop is placed upon the moistener plate as indicated by Fig. 3, and moved forward, the flap *b* thereof will engage below the reëntrant or cut-away portion 10 of the flap and envelop director, and be directed downwardly thereby, and as the envelop is moved still farther in the direction of the arrow, Fig. 3, and as indicated by Fig. 4, the body portion of the envelop 15 at the sides thereof will engage the side portions of the flap and envelop director which by its outwardly-curved contour will direct the envelop as a whole upwardly over the top of the flap and envelop director, thus drawing the flap of the envelop over the moistener 20 plate 15. Owing to the construction of the flap and envelop director which provides the central reëntrant or cut-away portion and downwardly-inclined side portions, this action of the flap and envelop director will take place whenever an envelop is moved over the moistener plate with its flap turned as indicated by Fig. 3, regardless of whether the pressure of the hand upon the moistener 25 plate has been sufficient to bring the plates into position substantially as indicated by Fig. 4. In other words, the flap of the envelop will engage the reëntrant or cut-away portion of the director and be directed 30 downwardly thereby, and the side portions of the envelop will be engaged by the side portions of the director and be directed upwardly thereby, regardless of whether the pressure on the moistener plate has been effective in bringing the moistener and sealer 35 plate into a common plane, as indicated by Fig. 4, or not.

The under portion of the envelop flap and envelop director 35 is preferably provided with an inclined surface 39, Figs. 2, 50 3, and 4, which facilitates the direction of the flap *b* of the envelop downwardly and into coöperative relation with the moistener 45 as the envelop is moved over the moistener and sealer plates.

If desired, the sealer plate 18 may be provided with a pad 40 to engage with the extensions 30 of the arm 27 when the hand depresses the plates into a common plane, as indicated by Fig. 4. Likewise, the moistener plate 26 may be provided with pads 41 for resting upon the stops or projections 55 when the parts are in normal position.

From the construction above-described as 60 the preferred form of the present invention,

it will be noted that the flap and envelop director unerringly secures the downward movement of the envelop flap into coöoperative relation with the moistener, and that the side portions of the flap and envelop director equally insure upward movement of the body of the envelop, and consequently the wiping of the envelop flap over the moistener 15 and its subsequent sealing as the envelop is forced forward from the moistener to the sealer plates. 75

While the construction described is found to be an effective embodiment of the present invention, it is to be understood that changes in details may be made within the true scope 80 of the actual invention which is defined by the claims.

What is claimed is:

1. In an envelop moistener and sealer, the combination of a frame, a moisture supplying device associated therewith, moistener and sealer plates connected to said frame, and sustained with the central edge portion of the sealer plate above the edge of the moistener plate to direct the flap of an envelop downwardly and the side edge portions of the sealer plate below the edge of the moistener plate to direct the body of the envelop upwardly as the envelop is moved over said plates. 95
2. In an envelop moistener and sealer, the combination of a frame, a moisture supplying device associated therewith, moistener and sealer plates connected to said frame, said sealer plate having a flap and envelop 100 directing edge provided with a central reëntrant or cut-out portion and downwardly extending side portions, and means for sustaining said moistener and sealer plates with the edge of the reëntrant or cut-out portion of the latter above the edge of the moistener plate to direct the flap of an envelop downward and the side portions of the sealer plate below the edge of the moistener plate to direct the body of an envelop 105 upward as it is moved over the said plates. 110
3. In an envelop moistener and sealer, the combination of a frame, a moisture supplying device associated therewith, a depressible moistener plate, a sealer plate provided with a flap and envelop director having a recessed central portion and downwardly extending side portions, yielding means for sustaining one of said plates, and connections between said plates for causing 115 the depression of one by the depression of the other. 120

4. In an envelop moistener and sealer, the combination of a frame, a moisture supplying device, depressible moistener and sealer plates having their edges separated, said sealer plate having a flap and envelop director provided with an edge portion curved downwardly from the center toward each side of said director, and yielding 125 130

means for supporting said plates with the central edge portion of the director above the adjacent edge of the moistener plate and the side edge portions of said director 5 below the edge of the moistener plate.

5. In an envelop moistener and sealer, the combination of a frame, a moisture supplying device, depressible moistener and sealer plates having their edges separated, said 10 sealer plate having a flap and envelop director provided with an edge portion curved downwardly from the center toward each side of said director, and yielding means for supporting said plates with the 15 central edge portion of the director above the adjacent edge of the moistener plate and the side edge portions of said director below the edge of the moistener plate, and a stop for limiting the action of said yielding 20 means.

6. In an envelop moistener and sealer, the combination of a frame, a moisture supplying device associated therewith, a moistener plate and a sealer plate, the latter being 25 provided with a flap and envelop director having a recessed or cut-away central portion and downwardly-extending side portions, and means for sustaining said plates with the recessed portion of the director 30 above the edge of the moistener plate to engage the flap of an envelop and turn it downwardly and the side portions below the edge of the moistener plate to engage the body of an envelop and direct it upwardly as the envelop is moved over said 35 plates.

7. In an envelop moistener and sealer, the combination of a frame, a moisture supplying device associated therewith, a moistener 40 plate and a sealer plate, the latter being provided with a flap and envelop director having a recessed or cut-away central portion provided with a flap-engaging inclined

surface, and downwardly-extending side portions, and means for sustaining said 45 plates with the recessed portion of the director above the edge of the moistener plate to engage the flap of an envelop and turn it downwardly and the side portions below the edge of the moistener plate to engage 50 the body of an envelop and direct it upwardly as the envelop is moved over said plates.

8. In an envelop moistener and sealer, the combination of a frame, a moisture supplying device associated therewith, a depressible moistener plate, a sealer plate, means for forcing one edge of the sealer plate upward, connections between the sealer plate and moistener plate, and a stop carried by 60 said connections to limit the action of said means and cause the said plates to be normally positioned with the central portion of the sealer plate edge above and the side 65 portions below the edge of the moistener plate.

9. In an envelop moistener and sealer, the combination of a supporting frame, a moistener plate 26, and a sealer plate 18, said 70 sealer plate being provided with a flap and envelop director 35 provided with a central cut-away or recessed portion 37 and downwardly-curved side portions 38, and a spring for sustaining said moistener and sealer plates with the cut-away or recessed 75 portion 37 of the said director 35 above and the side portions 38 below the edge of the moistener plate.

In testimony whereof, I have signed my name to this specification, in the presence 80 of two subscribing witnesses.

CLARE H. DRAPER.
